UNITED STATES PATENT OFFICE.

EVERETT P. RICHARDSON, OF LAWRENCE, ASSIGNOR TO THE MCKAY & THOMPSON CONSOLIDATED LASTING MACHINE ASSOCIATION, OF BOSTON, MASSACHUSETTS; GORDON MCKAY, OF NEWPORT, RHODE ISLAND, PRINCIPAL TRUSTEE.

LASTING-MACHINE.

SPECIFICATION forming part of Letters Patent No. 311,850, dated February 3, 1885.

Application filed January 3, 1882. Renewed September 22, 1884. (No model.)

To all whom it may concern:

Be it known that I, EVERETT P. RICHARDSON, of Lawrence, county of Essex, State of Massachusetts, have invented an Improvement 5 in Lasting-Machines, of which the following description, in connection with the accompanying drawings, is a specification.

In the machine herein described the action 10 of the gripping jaws or device is substantially that practiced by hand-lasting with nippers, with, however, the advantage of simultaneously stretching and drawing the edges of the upper about the last from two opposite points, and from opposite sides of the last toward the 15 center line of the bottom of the last.

My invention consists in a nail-driving lever directly actuated in one direction by means of a treadle, and in the other direction by means of a spring.

20 My invention also consists in upper gripping jaws or devices to engage and draw the upper by its opposite edges about the last, combined with mechanism at each side of the last, and co-operating with the said jaws or devices, to automatically drive nails or fastenings into the said upper and inner sole to confine them together.

My invention also consists in a novel method 30 of lasting, as will be hereinafter described and claimed.

My invention also includes an inner-sole presser, which is located near the jaws which grasp the upper, and which, interposed between the edge of the upper and inner sole, holds the latter down snugly upon the last while the upper, near the presser, is drawn and nailed, and also in organizations of mechanical elements, as will be hereinafter fully set forth in the claims at the end of this specification.

Figure 1 represents in side elevation a sufficient portion of a lasting-machine to illustrate my invention; Fig. 2, a front elevation of Fig. 1; Fig. 3, a section on the dotted line *xx*, (see Fig. 2;) Fig. 4, a detail to be referred to; Fig. 5, an enlarged view of the rear side of the upper part of one-half of my machine; Fig. 6, a view of Fig. 5 from the right. Figs. 7 and 8 are sec-

tional details taken through the shanks of the jaws and their friction device, and through 50 the lever which, pivoted upon one jaw, actuates the other jaw to cause the two jaws to at times move separately and thereafter together; Fig. 9, an enlarged detail of the acting or forward ends of the gripping-jaws to receive the 55 upper; Fig. 10, a detail to be referred to; and Fig. 11, a detail showing the addition to the machine of an inner-sole presser, omitted from the other figures to avoid confusion of parts.

The base or standard *a*, of suitable height, 60 has at its upper end a plate, *a'*, which has secured to it the two standards *b b*, which receive and guide the gripping-jaws and the nail-driving mechanism, to be described. Each standard, its upper gripping devices, and nail or 65 tack driving mechanism being alike, I need to specifically describe but one of them. The standard *b* at its upper end has a cross-head, *b'*, in which is a horizontal guideway, as shown in Figs. 1, 6, 7, and 8, that receives in it the shanks of the two upper-gripping jaws *c d*. The shank of jaw *d* is recessed along one side to receive the shank of jaw *c*, and is slotted at *d'* (see Fig. 5) to receive through it the friction device *e*, shown as a round rod attached to the upper end of a spring-arm, *e'*, connected with the rigid or fixed part *b'*. This friction device, by its action on the shank of jaw *e*, prevents its being moved by simply the friction against it of the moving jaw *d*. The 80 jaw *c* is provided at one side (see Figs. 5 and 8) with a stud, *c'*, which, extended through a slot, 2, in the shank of jaw *d*, serves as the fulcrum for the short jaw operating and carrying lever *c''*, the lower end of which is engaged and moved by the jaw-actuating lever *f*, pivoted at *f'*. The lever *c''* is provided with an elongated slot, as shown at Fig. 5, at a point between its fulcrum and its free end, and receives in the said slot a stud, *d''*, secured 90 to the shank of jaw *d*. The acting front end 3 of jaw *c* is made as a hook, with, preferably, a serrated inner face, as shown in Figs. 5 and 9, to engage the upper at the inner side of its edge, or between the upper and the inner sole, 95 while the front or acting end 4 of jaw *d*, also

preferably serrated, is made wedge-shaped, to come against the face or outer side of the edge of the upper and grasp the said edge between the two portions 34, the said parts once closed 5 upon the edges of the upper holding the said edges clamped forcibly between them, while the jaws are moved forward together to carry the edge of the upper held between them over upon the inner sole, where the upper 10 is nailed or secured before the jaws release their hold upon it. The jaw *d* has secured to and carries back and forth with it a plate, *g*, curved at its front end, as in Fig. 5, and provided with a channel, *g'*, as in Fig. 10, to receive the string-nail material *g''*, of usual construction, held on a spool, *g'*, pivoted to the standard *g'*, rising from the plate *g*. This string-nail material, in common use in nailing-machines, passes under a detent or 15 shield, *h*, also common to other nailing-machines. The plate *g* at its front end has on its groove a small steel cutting-block, *g'*, which serves as one member of the cutting device, which severs each nail as it is driven from the 20 next nail back of it in the string of nails. The head of the second nail back of the one last driven is acted upon and held from moving backward by the detent *h*. The other member of the cutter is the steel block *k*, which 25 forms the main part of the nail-driver, or that part which directly engages the head of the nail. The block *k* has at its upper edge a rib, *b*, which enters a corresponding groove in a lever attached to the driver-carrier, (herein 30 shown as a lever, *k'*.) This lever is pivoted at *k'* to the plate *g*. The block *k* is held upon the lever somewhat loosely by the screw 7 and the pressure of the spring 18, such loose connection permitting the block to move out 35 40wardly, during the upward movement of the driver-lever *k'*, sufficiently to pass the head of the nail next to be driven, thus putting the block *k* in position to engage the said head at its next descent. The spring 18 keeps the 45 block pressed against the front edges or sides of the nails of the string of nails as they are to be driven.

To limit the descent of the lever *k'* when thrown down by spring *l* to drive a nail, the 50 plate *g* has extended from it a part, *m*, provided at its upper side with a yielding cushion, *m'*, to lessen shock and noise. The spring *l* at its upper end is connected with the rod *l'*, which is pivoted to the stud *r'* of the ear *l'* of lever *k'*, and at its lower end the spring *l* is 55 joined with the adjustable yoke *n*, fixed upon the rod *n'*, secured to the bracket *a'* of the standard *a*. The lower end of rod *l'* (shown in section, Fig. 3, and in detail, Fig. 4) has a 60 projection, *8*, (see Fig. 4,) which rests upon a shelf or projection, *g*, of the cross head *p'*, carried by the slide-rod *p'*, having on it a grooved cross-head, *p''*, which receives a roll or crank-pin, 12, on the disk *r* of an intermittently-rotating power-shaft having fixed upon it one member, *r'*, of a friction or clutch pulley, the other or loose member, *r''*, about which the driv-

ing-belt will extend, being under the control of a treadle and intermediate devices, whereby the clutch-pulley may be separated and 70 the movement of the disk and crank bestopped after each complete revolution, and remain at rest until the clutch-pulley is again engaged by the operator. The lower ends of rods *l* are kept upon the shelves 9 of the cross-head *p'* by the 75 inclined positions of the springs *l*, and as the cross-head is raised the said rod is lifted to lift the driver-levers *k'*, as in Fig. 5, and strain the springs *l*; but as soon as the cross-head reaches a certain position in its upward movement, 80 at which time the jaws are supposed to have reached their farthest forward positions, with the edges of the upper between them, the ends of the rods are acted upon by the pawls *p*, pivoted upon the yoke *n*, (the said pawls 85 being then brought into nearly horizontal position,) which push the said rods from the shelves 9 and allow the springs *l* to act and throw down the arms *k'* and block *k*, the latter engaging the head of a string-nail and driving 90 it into the upper and into the inner sole on the last at one side of the jaws, which then grasp and hold it. The block *k* in its downward movement against the head of the nail, as the block arrives opposite the steel edge *g'*, 95 before referred to, cuts the nail, the body of which has been partially driven, and severs it from the string of nails. The block *k*, when driving a nail, moves the string of nails with it, and thus acts to feed the nail-string forward. 100 The wedge *s* at the upper end of the bar *s'*, pivoted to the lever *s'*, and having its fulcrum at *s''*, as the bar *s'* is moved in the direction of the arrow, acts upon the hub of the loose member *r''* of the clutch-pulley and causes the 105 members *r'* *r''* to be forced together to rotate the disk *r* and crank-pin once. The lever *s'* is acted upon by a spring, 22, (shown only in Fig. 1,) which places the lever and wedge *s* in such position that the clutch-pulley parts 110 are not pressed toward each other with sufficient force to run together. The free end of the lever *s'*, acted upon by the said spring 22, is held up, as shown in Fig. 1. The link *s'*, having a projection, 15, located at one side of it, 115 and just above the free end of lever *s'*, is joined with a treadle, *t*, having its fulcrum at *t'* on the treadle-carrying arms *t'*, which have their fulcrum at *t''*, a spring, *t'*, rigidly connected at one end with the standard *a*, serving to 120 keep the arms *t'* lifted, as in Figs. 1 and 2, and with the pin 17 of the link *s'* against the bracket *a'*. A spiral spring, *u*, or it might be a weight, keeps the link pulled in such direction that the projection 15 will catch over 125 the end of lever *s'*. The pin 16 controls the point to which the lever *s'* and the front end of the treadle *t* may descend. The arms *t'* have connected with them the links or connecting-rods *w*, which at their upper ends are 130 joined with the lower ends of the jaw-moving levers *f*, pivoted at *f'*, the said levers being adapted at their other ends to engage the ends of levers *c'*.

Referring to Fig. 5, the front ends, 3 4, of the horizontally-movable jaws or grippers *c d* are shown as opened to receive between them the edges of the upper. Both pairs of these 5 jaws at opposite sides of the last and upper to be lasted are in like condition, and have like movements given to them simultaneously. The edge of the upper having been placed between the ends of the said jaws, the operator, 10 with his foot upon the treadle *t*, will depress or push down the arms *t*² from their full to their dotted line position, leaving, however, the treadle *t* on its dotted-line position, which will so actuate the levers *f* and *c*² as to produce the following movements in the jaws *c d*, 15 viz: The lever *f* will move the lower end of the lever *c*² to the right, (see Fig. 5,) and cause lever *c*² by its action on the pin or stud *d*² of the shank of jaw *d*, to carry the said jaw *d* forward, 20 the jaw *c* being then held by the friction device *e* until its end 4 is made to clamp the edge of the upper firmly between it and the end 3 of jaw *c*. At about this time the lower end of the lever *c*² has been swung toward the 25 right about its fulcrum *c*², connected with the shank of jaw *c*, so that it occupies a position substantially as indicated in dotted lines, Fig. 5, at which time the centers *c*², *d*², and *f*² will be in such line with relation to each other that 30 further movement of levers *f* and *c*² will cause the two jaws *c d* to be moved forward in unison, they clamping or gripping the upper firmly between their parts 3 4, and drawing and stretching the upper about the last by a 35 direct pull thereon from substantially opposite points and from opposite sides of the last; the said jaws passing over the inner sole upon the bottom of the last and carrying with them the edges of the upper, to be automatically nailed 40 or fastened to the inner sole while so held by the jaws. The driver-lever having been thrown down to drive a string-nail, as will be described, by the spring *l*, after the action of the pawls on the rods *l*, the arms *t*² are permitted to rise, 45 and the lever *f* is moved in the opposite direction. At first the jaw *d* is started by itself, the jaw *c* being held by the friction device *e*, and moved back far enough to release the edge of the upper, after which the two jaws are 50 carried backward together, and the last and upper thereon moved, preferably by hand, far enough to enable the jaws to be again closed upon that part of the edge of the upper to be next clamped and drawn over upon the inner sole, as just described. During the time that the 55 jaws are opened or separated and the last, with the upper on it, is being moved for the next operation, the edges of the upper are kept between the jaws, and jaw *c* is moved back 60 far enough for the edge of the upper to come in contact with the part 24 of the jaw *c*.

In Fig. 1 the wedge *s* is not lifted quite enough to cause the operative engagement of the clutch-pulley, and the crank-pin 12 is substantially in the same horizontal plane as the center of the shaft on which is the disk *r*, that carries the crank-pin 12. As the arms *t* are

depressed into the dotted-line position, Fig. 1, to close and move the jaws forward, the front end of treadle *t* is kept elevated by the greater pressure of the heel on the treadle, so as to keep rod *s*² lifted and the pin 17 against bracket *a*², and consequently when arms *t*² are down, as in dotted lines, the treadle *t* is as in dotted line. The upper having been drawn over upon the inner sole by the jaws and to the satisfaction of the operator, he will turn the treadle *t*, push down its front end, depress the rod *s*², and cause its projection 15 to turn the lever *s*², lift the bar and wedges, and force the clutch-pulley parts so closely together as to cause the loose but running part *r*² to pick up the fast part *r*² and turn the disk *r* and crank-pin 12 to completely lift the partially-lifted cross-head *p*², further strain the springs *l*, push off the links *l*, and permit the springs *l* to operate the driver-lever and drive a nail, after which the motion of disk *r* will be continued until the cam *x* thereon strikes the upper end of rod *s*², pushes it outward, and removes projection 15 from above the lever *s*², when the disk *r*, having made one revolution, will stop, a suitable pawl, *x*², engaging a notch in the said disk, as shown in Fig. 2, to hold it at rest. When the disk stops by reason of lowering the wedges, the cross-head *p*² has been lifted sufficiently to elevate the lever *k*² to nearly its highest position from which it started when the clutch-pulley was engaged, as described. The jaws are closed and moved forward by manual power applied through the treadle by the foot of the operator, and may thus be made to stretch the upper more or less, according to its particular needs and strength; but the nail-driving mechanism is operated at the proper time automatically to drive the nails into the upper. The driver-lever, being pivoted upon the jaws, always occupies the same position with relation to the upper-grasping portions of the jaws, no matter how far they are moved over the edge of the inner sole, which is preferable to employing jaws to pull the upper forward and place it under a stationary nail tube or post in which a driver is made to reciprocate, as has been done in other machines. The usual inner sole, (see Fig. 11,) a part of which is shown at 25, and which will be laid in the last 26, all as usual, is apt to become lifted or curled up if very soft; but to avoid this I have attached to the jaw *c* by screws 27 and 28 a standard, 29, to the upper end of which at 30 I have pivoted the inner-sole presser 31, the lower end of which is curved, as shown, to form a foot to bear upon the inner sole near its edge and keep it down upon the last, while the end 33 of the said presser bears against the edge of the last; so as not to move the inner sole laterally.

In this my improved machine the upper is 130 grasped or engaged at two opposite points, and is drawn and stretched about the last at such points and from opposite directions by a direct pull, each jaw operating as do pinchers

actuated by hand, and then the upper, immediately when it is grasped, is automatically nailed fast to the inner sole. After this the shoe is moved a little, and the jaws again grasp 5 the edges of the upper near where they grasped it when they were last moved forward, and again draw such adjacent parts of the upper about the last from opposite directions, when the edges of the upper are nailed to the inner 10 soles, as before. The jaws thus operate successively and regularly on the upper, a part at a time, along the whole sides of the last, each movement of the jaws partially drawing upon and stretching parts of the upper, which will 15 be more fully stretched at a subsequent operation of the jaws. In this way I am enabled, when starting, say, from near the toe, to gradually draw and fit the upper to the curvatures of the upper part of the last.

20 I am aware that the upper has been engaged at opposite sides of the last by pullers.

I claim—

1. The two pairs of jaws to grasp the upper between them at its opposite sides and carry 25 its edges forward simultaneously over the edge of the inner sole and stretch the upper by a direct pull, combined with two nail-driving mechanisms, substantially as described, adapted to automatically drive nails or fastenings into the upper and inner sole while the edges of the upper are clamped between the said jaws, substantially as set forth.

2. The two pairs of movable jaws located 30 opposite each other at opposite sides of the last, and their friction devices to hold one member of each pair of jaws at rest while the other members are being moved forward to grasp or clamp between them, as described, the edges of the upper at opposite points and at 35 opposite sides of the last, and means to move the said jaws toward each other, substantially as described, while clamping the upper between them, combined with two drivers and springs to actuate them to drive fastenings 40 into the upper and inner sole while the edges of the upper are grasped between the said jaws, and after the upper has been drawn from opposite sides of the last by the said jaws, and is held stretched over the last, as set forth.

50 3. The movable jaws *c d*, the plate *g*, made movable with jaw *d*, and adapted to guide the string-nails, and the cutting device attached to the said plate, combined with the driver lever and block to engage the head of and 55 drive the nail, the spring to actuate the driver-lever, the rod *l* to lift the driver-lever, and means, substantially as described, to move the rod and permit the said spring to depress it and the drive-lever, substantially as set forth.

60 4. The string-nail-guiding plate *g* and its cutting member *g*, combined with the spring-operated driver and its block to engage the head of and drive a nail, and, by its co-operation with the cutting member *g*, sever the nail 65 being driven by it from the string of nails.

5. The jaws *c d*, combined with the movable

lever *c*, pivoted upon jaw *c*, and connected with and so as to move the jaw *d* separately, and then both jaws *c d* together, substantially 70 as described.

6. The jaws *c d*, the lever *c*, pivoted upon one jaw, and connected with and so as to move the other jaw separately, and then both jaws in unison, and the friction device to act upon 75 the jaw *c*, combined with means, substantially as described, to operate the said lever *c*, as and for the purposes set forth.

7. The two horizontally-reciprocating jaws *c d*, combined with the driver-lever pivoted 80 upon and made movable horizontally with the said jaws, to drive a nail in the same relative position with relation to the jaws, whatever may be their inward position.

8. The two horizontally-movable jaws *c d*, 85 the plate *g*, and the driver-lever pivoted to it, combined with the rest *m*, adapted to arrest the descent of the driver-lever, substantially as described.

9. The two horizontally-movable jaws, the 90 string-nail-guiding plate carried thereby, and the detent to prevent backward movement of the string-nail material, combined with the driver-lever and driver-block to drive the string-nails, all being adapted to reciprocate 95 backward and forward together toward and from the center of the last, substantially as and for the purpose described.

10. The arms *t*, rods *w*, levers *f*, and jaws *c d*, moved thereby, substantially as described, 100 the treadle *t*, made movable both with the said arms *t* and independently of them, and with the friction or clutch pulleys, combined with the rod *s* and means, substantially as described, to engage the said pulley parts at the desired 105 time, substantially as set forth.

11. The rod *p*, its cross-head *p*, provided 110 with projections *8*, means, substantially as described, to operate the cross-head, links or rods *l*, driver-levers, and springs to actuate them to drive nails, combined with the pawls to remove the said links or rods from the said projection, substantially as described.

12. The herein-described method or process 115 of lasting a shoe, which consists in placing the upper on the last provided with an inner sole, grasping opposite edges of the upper at opposite sides of the last between jaws, drawing the said upper over on the inner sole by a direct pull thereon by the said jaws, which 120 grasp the upper between them, driving nails or fastenings into the edges of the said upper while held clamped between the said jaws, then opening the said jaws, retaining the edges of the upper between the faces of the opened jaws, moving the upper and last horizontally 125 to bring between the open jaws those parts of the upper at opposite sides of the last which are next to be grasped between the jaws, and closing the said jaws upon the upper preparatory to again moving the said jaws forward, substantially as described.

13. The two pairs of jaws to grasp the edges of the upper between them at its opposite

sides and draw and stretch the upper about the last, combined with two nail-driving mechanisms adapted to automatically drive nails or fastenings to secure the upper to the inner sole, substantially as described.

14. The string-nail guide g and its cutting member g^5 , combined with a spring-operated driver adapted to engage the head of and drive a nail and assist in severing the nail from the

string of nails as the nail is being driven, substantially as described.

In testimony whereof I have signed my name to this specification in presence of two subscribing witnesses.

EVERETT P. RICHARDSON.
